HEATING STOVE

Victor L. Cook, Pewamo, Mich.

Application August 24, 1937, Serial No. 160,689

3 Claims. (Cl. 126—72)

This invention relates to heating stoves, and particularly to stoves of that type designed for heating air for circulation in a room or enclosure to be heated.

5 The primary object of the invention is to provide a stove of this character embodying a novel construction and arrangement of tubes for conducting the air through the stove from the bottom portion to the top portion of the stove and so formed and disposed as to heat a large volume of air within a given time and in a most effective manner with a minimum consumption of fuel.

10 A further object of the invention is to provide heating tubes grouped to form a conduit for travel of the products of combustion from a heater to an outlet flue so as to secure a heating effect on the tubes substantially through the travel of the combustion products, the lower ends 15 of which tubes are arranged within the area of greatest heat transfer and so bent at an angle to their upper ends and flattened transversely as to increase the extent of the area thereof exposed directly to the flames of the 20 heater and simultaneously produce a checking action whereby the speed of flow of air through the tubes is reduced to promote the heating of the air flowing therethrough within any given 25 period of time.

30 With these and other objects in view, the invention consists of the features of construction, combination and arrangement of parts, hereinafter fully described and claimed, reference being had to the accompanying drawings, in which:

35 Fig. 1 is a perspective view, with parts in section, of a heating stove embodying my invention.

Fig. 2 is a vertical transverse section, on line 2—2 of Fig. 3, through a modified construction 40 of stove.

Fig. 3 is a horizontal section on line 3—3 of Fig. 2.

45 Referring now more particularly to Fig. 1 of the drawings, a heating stove is shown comprising a stove body, casing or drum 1 of cylindrical or other suitable form and having a top head 2, a bottom head 3 and an interior horizontal partition 4, said partition 4 being of annular form and dividing the interior of the stove into a bottom chamber 5 and a relatively deeper top chamber 6 in communication through the central opening 7 of the partition 4.

50 The stove body may be supported upon legs 8, disposing the bottom head 3 a suitable distance above the floor line, and in the upper por-

tion of the body 1 is an outlet 9 for the discharge of the combustion heating gases, which communicates with the chamber 6 and with an outlet flue 10.

5 The bottom head 3 is provided with a central opening 11 for the passage of the neck portion of a burner 12 of suitable type, the burner portion proper 13 of which extends upwardly and centrally within the lower portion of the chamber 5. This burner may be an oil burner, a gas 10 burner or a burner designed for using any type of fuel, and it may be either permanently or removably secured in position. A burner removably secured in position is shown in the present instance, the body or fount portion of 15 which is secured to the underside of the head 3. At one side of the chamber 5 a doorway or opening 14, closed by a suitable door 15, is provided to permit access to the chamber 5 for cleaning, repairs or other purposes, as well as 20 for inspection of the burner.

25 Disposed vertically and axially within the drum 1 is a series of air heating tubes 16. These tubes extend through the opening 7 in the partition 4 and are secured to and open at their upper and lower ends through the heads 2 and 3, for the circulation of air upwardly there-

20 through from the bottom to the top of the stove and through the upper ends of the tubes out into the room or enclosure to be heated. The tubes 30 may be arranged in an annular groove or disposed in any suitable manner so that their portions disposed within the chamber 6 will pro-

35 vide a central passage 17 for the upward travel of the products of combustion from the burner substantially throughout the length of the tubes so that the full heating effect of such products will be obtained before they exhaust through the outlet 9, the tubes being suitably spaced 40 from one another to allow the products to pass through such spaces and about the tubes and between the passage 17 and the circumambient portion of the chamber, so that all surfaces of the tubes will be exposed to the products for a heating action. As shown, the lower vertically 45 disposed inlet ends 18 of the tubes, arranged within the chamber 5, are spaced a greater distance apart than the vertical portions 19 of the tubes mainly disposed within the chamber 6, said lower ends 18 of the tubes being connected with 50 the portions 19 by inwardly offset or bent portions 20 which are arranged so as to project inwardly to lie within the direct heating zone of the burner 13, that is, so as to be contacted by the flames from the burner, whereby the 55

tubes will be directly and highly heated at such points. From this point the flames and products of combustion from the burner travel upward through the opening 7 and in contact with the portions 19 of the tubes, by means of which a highly efficient heating action will be secured by direct contact of the products with the tubes until such products discharge through the outlet 9. The arrangement is also such that the products of combustion also fill the chamber 6, so that heat by radiation through the walls of the drum 1 will also be secured. The heated air issuing from the outlet ends of the tubes 17 may be employed to heat the room or enclosure in which the stove is arranged or by the use of suitable conducting flues to heat other rooms or enclosures.

At the points 21 where the tube bends 20 connect with the tube portions 19 the bends are somewhat flattened or otherwise suitably constricted for the purpose of securing Venturi action or effect in producing a pulsating or jet action of a suitable degree to cause the more rapid drawing in of air through the inlet ends of the tubes and a more rapid circulation of the air on their flow through the tubes, by which means a larger volume of air may be caused to pass through the tubes and to be heated within a given period of time than by the use of tubes of uniform diameter. Thus by the novel formation and arrangement of the offset portions 20 of the tubes, which are directly heated by the flames of the burner, and by the provision of the constricted portions 21 and the grouping of the tube portions within the chamber 6, a higher heating effect is obtained, the volume of air flowing through the tubes increased and a long range heating action obtained allowing a larger volume of air to be heated within a given time at the expenditure of a minimum amount of fuel.

In Figs. 2 and 3 I have shown a modified form of my invention wherein the general construction of the stove is the same, but tubes of modified construction are employed. In this modified construction the lower or inlet ends 18' of the tubes 16' open through the sides of the wall portions of the drum forming with the head 3 and partition 4 the bottom chamber 5, and said ends of the tubes thence extending horizontally inwardly to points above the burner, where the lower extremities of the body portions 19' of the tubes are disposed in annular formation, which is continued the full distance upward from the inner ends of the portions 18' to the points where the tubes are connected with the upper head 2. As shown, the inner extremities of the horizontal inlet portions 18' of the tubes and the portions of the vertical limbs of the tubes 16' which are disposed in the chamber 5 are flattened or reduced to a substantially elliptical form to increase their lateral extent and amount of surface exposed to the flames of the burner 13. At the points of bend between the horizontal and upright portions of the tubes the tubes are constricted as shown at 21' so as to produce the Venturi action or effect heretofore referred to, which is promoted and increased in this structure owing to the flattened tube formation. This type of tube structure has all the advantages of that shown in Fig. 1 and in addition provides a greater area of heating surface of the tubes exposed directly from the flames of the burner for the air heating action. The operation of this form of the invention will be readily under-

stood from that previously explained with reference to the structure shown in Fig. 1.

From the foregoing description, taken in connection with the drawings, the construction of my improved heating stove will be readily understood and it will be seen that it provides a stove for heating air which embodies a novel construction and arrangement of heating tubes by means of which the heating action is increased and the amount of air heated within a given time also increased with the use of a minimum amount of fuel, so that while an increased heating action is obtained a low consumption of fuel is also ensured. While the structures shown are preferred, it will, of course, be understood that changes in the form, construction and arrangement of parts, within the scope of the appended claims, may be made, without departing from the spirit or sacrificing any of the advantages of the invention.

What I claim is:

1. A heating stove comprising a casing having an outlet flue for discharge of products of combustion at or near its upper end, a horizontal partition arranged below the horizontal center of the casing and dividing said casing into upper and lower chambers, said partition having a central opening therein for upflow of products of combustion from the lower chamber to the upper chamber, a burner centrally disposed in the lower chamber of the casing in line with said opening, and a group of air heating tubes extending substantially from top to bottom of the casing through the opening in the partition and annularly arranged around the opening and open to the atmosphere at their upper and lower ends, the upper portions of said tubes being vertically disposed in the upper chamber in spaced relation to each other and the lower portions of said tubes being grouped about the burner and spaced from each other, the lower portions of the tubes lying below and in immediate proximity to the partition and between the same and the burner being bent to provide horizontal branches and having their bends overlying the burner and constricted to check the flow of air therethrough at the area of greatest heat transfer.

2. A heating stove comprising a casing having an outlet flue for discharge of products of combustion at or near its upper ends, a horizontal partition arranged below the horizontal center of the casing and dividing said casing into upper and lower chambers, said partition having a central opening therein for upflow of products of combustion from the lower chamber to the upper chamber, a burner centrally disposed in the lower chamber of the casing in line with said opening, and a group of air heating tubes extending substantially from top to bottom of the casing through said opening and annularly arranged around the opening and open to the atmosphere at their upper and lower ends, the upper portions of the tubes being vertically disposed in the upper chamber in spaced relation to each other and the lower portions of said tubes being grouped about the burner in the lower chamber and spaced a greater distance apart than their upper portions, said lower portions of the tubes having upper and lower vertical branches connected by bent portions forming substantially horizontal branches disposed below and in proximity to the partition and overlying the burner and having their bends constricted to check the flow of air therethrough at the area of greatest heat transfer.

therethrough at the area of greatest heat transfer.

3. A heating stove comprising a casing having an outlet flue for discharge of products of combustion at or near its upper end, a horizontal partition arranged below the horizontal center of the casing and dividing said casing into upper and lower chambers, said partition having a central opening therein for upflow of products of combustion from the lower chamber to the upper chamber, a burner centrally disposed in the lower chamber of the casing in line with said opening, and a group of air heating tubes extending substantially from top to bottom of the casing through the opening in the partition and annularly arranged around the opening and open to

the atmosphere at their upper and lower ends, the upper portions of the tubes being vertically arranged in the upper chamber in spaced relation to each other and the lower portions of said tubes being arranged within the lower chamber 5 and bent to provide vertical branches and horizontal branches, the latter being disposed below and in proximity to the partition, and said vertical and horizontal branches being connected by bends directly overlying the burner, 10 said branches of the lower portions of the tubes being flattened to increase their heating areas and retard the flow of air therethrough in the area of greatest heat transfer.

15 VICTOR L. COOK.
